UNITED STATES PATENT OFFICE.

CYRILLE BELANGER AND JOHN CARON, OF QUIMBY, MAINE.

RAILWAY CONSTRUCTION.

Application filed April 8, 1922. Serial No. 550,828.

To all whom it may concern:

Be it known that we, CYRILLE BELANGER and JOHN CARON, citizens of the United States, residing at Quimby, in the county of Aroostook and State of Maine, have invented new and useful Improvements in Railway Constructions, of which the following is a specification.

Our present invention has reference to 10 railway construction.

Our object is to produce a simple, cheap and effective joint for railway rails, wherein the employment of fish plates, angle bars and analogous devices will be entirely dispensed with.

The foregoing, and other objects which will appear as the nature of the invention is better understood, may be accomplished by a construction, combination and operative 20 association of parts, such as is disclosed by the drawings which accompany and which form part of this specification.

In the drawings:—

Figure 1 is a side elevation of rails constructed and connected in accordance with this invention.

Figure 2 is a sectional view on the line 2—2 of Figure 1.

Figure 3 is a sectional view on the line 30 3—3 of Figure 1.

Figure 4 is a sectional view on the line 4—4 of Figure 2.

Figure 5 is a perspective view of one of the rail ends.

Figure 6 is a similar view of a cooperating 35 pair of connecting plates.

The rails R have their body portions of the ordinary construction, each including a head 1, a base flange 2 and a web 3 connecting the head and flange. The rails, however, at their ends have their sides enlarged, the outer faces of the said enlargements being flush with the sides of the heads. The enlarged portions of the rails are channeled 40 longitudinally in a line with the outer faces of the webs 3 of the rails, thus providing pockets 4. The upper walls of the pockets are in a line with the under faces of the heads of the rails and the lower walls of the 45 pockets are in a line with the upper faces of the flanges of the rails. The outer walls of the pockets are parallel with the outer faces of the webs, the outer walls of the pockets being, for distinction, indicated by the 50 numeral 5. The walls 5 of the enlargements 55

or pockets have openings 6 therethrough which align with openings 7 in the webs 3 of the rails.

The base flanges of the rails are received in the edge flanges 8 of a rail chair 9, the 60 said chair resting on a supporting tie 10, and is spiked thereto.

When the rail ends are brought against each other, we insert through the opposite ends of the aligning pockets 4 of the respective rails R plates. The plates are in the nature of connecting members and are disposed in cooperating pairs. The plates are indicated by the numeral 11 respectively, and the confronting edges of the plates are 70

arranged at opposite angles. Thus the plates are wedge-shaped. The angle edges of the plates are, for distinction, indicated by the numeral 12. The angle edges 12 of the plates are provided with notches 13 designed 75 to align when the plates are brought to one position in the pockets and to register with the openings 6 and 7. When so arranged we

pass through the openings and through the notches, key members 14. The keys prefer- 80 ably have outer slotted ends and being constructed of malleable material, these ends 15

are spread away from each other against one of the walls 5 provided by the enlargement or pocket on one side of the rails. The 85 keys 14, contacting with the upper and lower walls of the notches 13 will spread the plates away from each other, causing the upper plate to contact with the upper wall of the pocket and the lower plate to contact with 90 the lower wall of the pocket, and in this manner it will be noted that the rails are not only effectively connected, but are supported at their meeting ends by the plates and keys.

Having described the invention, we 95 claim:—

1. Rails having their ends provided with aligning pockets, plates having opposed beveled confronting edges received in the pockets, and means passing through the 100 pockets and plates for contacting the plates to force the same away from each other and in contacting engagement with the respective upper and lower walls of the pockets.

2. Rails having their sides, at their ends thickened and the outer walls of the thickened portions being flush with the sides of the heads of the rails, said thickened portions being channeled in a line with the webs 105 of the rails and in a line with the under face 110

of the head and the upper faces of the bases to cause the same to contact with the respective upper and lower walls of the pocket and of the rails to provide pockets, plates arranged in pairs and inserted in the pockets, for also securing the plates in the pockets. ¹⁰ said pockets and plates having openings therethrough designed to align, and key members passing through the openings for spreading the plates away from each other

CYRILLE BELANGER.
JOHN CARON.
